US0D1066021S

(12) **United States Design Patent** (10) **Patent No.:** **US D1,066,021 S**
(45) **Date of Patent:** **** Mar. 11, 2025**

(54) **PACKAGING SLEEVE**

(71) Applicant: **CASCADES CANADA ULC**, Kingsey Falls (CA)

(72) Inventors: **Marc Saint-Laurent**, Saint-Jean-sur-Richelieu (CA); **Sterling Andy Singh**, Montreal (CA); **Sophie Martraire**, Montreal (CA); **Romain Zolfo**, Montreal (CA); **Patrick Mainville**, Montreal (CA)

(73) Assignee: **Cascades Canada ULC**, Kingsey Falls (CA)

(**) Term: **15 Years**

(21) Appl. No.: **35/518,477**

(22) Filed: **Aug. 23, 2023**

(80) **Hague Agreement Data**

Int. Filing Date: **Aug. 23, 2023**

Int. Reg. No.: **DM/231578**

Int. Reg. Date: **Aug. 23, 2023**

Int. Reg. Pub. Date: **Sep. 29, 2023**

(30) **Foreign Application Priority Data**

Feb. 24, 2023 (CA) ..... CA 219470

(51) **LOC (15) Cl.** **09-03**

(52) **U.S. Cl.**

USPC **D9/761; D9/433**

(57) **CLAIM**

The ornamental design for a packaging sleeve, as shown and described.

DESCRIPTION

1. Packaging sleeve
2. Packaging sleeve
- 1.1: Top perspective view
- 1.2: Front elevation view
- 1.3: Back elevation view
- 1.4: First side elevation view
- 1.5: Second side elevation view
- 1.6: Top plan view
- 1.7: Bottom plan view
- 1.8: Unfolded bottom perspective view
- 1.9: Environmental top perspective view
- 2.1: Top perspective view
- 2.2: Front elevation view
- 2.3: Back elevation view
- 2.4: First side elevation view
- 2.5: Second side elevation view
- 2.6: Top plan view
- 2.7: Bottom plan view
- 2.8: Unfolded bottom perspective view
- 2.9: Environmental top perspective view

The broken lines are shown for the purpose of illustrating both parts of the article, as well as exemplary environmental subject matter. None of the broken lines form part of the claimed design.
